UNITED STATES PATENT OFFICE.

J. HARMAR KATES, OF PITTSBURG, PENNSYLVANIA.

PROPELLION OF VESSELS.

SPECIFICATION forming part of Letters Patent No. 363,244, dated May 17, 1887.

Application filed August 7, 1886. Serial No. 210,353. (No model.)

To all whom it may concern:

Be it known that J. J. HARMAR KATES, of Pittsburgh, in the county of Allegheny and State of Pennsylvania, have invented certain new and useful Improvements in the Propulsion of Vessels; and I do hereby declare the following to be a full, clear, and exact description of the same, reference being had to the accompanying drawings, forming a part of this specification, and to the figures and letters of reference marked thereon.

The object of my present invention is to increase the speed of vessels propelled by steam or other motive power; also, to utilize the available power of such motors over and above what can be employed to advantage in propelling the vessel; and this I accomplish by applying a portion of the motive power in a manner to increase the buoyancy of the vessel, and thereby decrease the resistance which would otherwise be opposed to its forward movement.

By the exercise of modern ingenuity and skill the power and capacity of motors proportional to their weight have been and will doubtless continue to be increased; but the increased power thus developed, if applied to vessels as ordinarily constructed, would not effect an equal gain in speed, owing to the fact that but a certain proportion of the power can be rendered available in propelling the boat, as is well understood.

Now, in practicing my invention, I propose to employ motors having greater power and capacity than are usually placed in vessels of the same dimensions, and to utilize the surplus power developed for acting upon or against the water in a manner and direction to not only propel the vessel, but also to raise the hull partially or wholly above the surface, thereby increasing its buoyancy and diminishing the resistance opposed to its forward movement.

I will first describe, in connection with the accompanying drawings, one of the simplest forms in which I propose to embody my said invention, after which I will point out the several novel features in the claims.

In the said drawings, Figure 1 is a side elevation of a vessel with the side bar removed, showing the application of my improvements. Fig. 2 is an end view, and Fig. 3 a side view, of one of my improved wheels. Figs. 4 and 5

are details showing the manner of mounting and operating the vertical, or, as I term them, "walking" floats.

Similar letters of reference in the several figures indicate the same parts.

The letter A designates the hull of the vessel, and B the propelling-wheels, of which latter there are preferably a series on each side of the boat.

The wheels B, which are of novel form and construction, are each composed of a hollow portion or drum, 1, provided on its periphery with a series of hollow floats or paddles, 2, whose operating or striking faces 3 are disposed at such an angle that when the boat is at rest they will strike and enter the water in a plane at or about parallel with the surface of the latter. The cylinders or drums 1 are of such dimensions and so arranged that their lower portion will project down at or slightly below the bottom of the hull A, and will be practically immersed when the boat is at rest, while the hollow floats or paddles 2 will extend below the bottom of the boat.

The floats 2 occupy about two-thirds the circumference of the wheel, and are made hollow and with the curved rear face or edge, 7, so that as they are successively immersed they will exercise a lifting-pressure on the shaft and boat to supplement that occasioned by the impact of the tangential or striking face, while the curved rear face, 7, will facilitate the entrance of water into the spaces between the floats and reduce the resistance offered by the water as the floats are raised or withdrawn.

As before mentioned, the lower side of the wheels B are immersed and the striking-face of the hollow floats are arranged on a line tangential to a circle touching the surface of the water or the normal water-line when at rest, as indicated by the dotted line *a a*, Fig. 1, so that the several cylinders or drums 1, together with the immersed floats 2, assist in supporting the hull above the surface of the water. If now the wheels B, constructed and arranged as described, and driven by powerful motors, be rotated rapidly and with great power in the direction indicated by the arrow in Fig. 1, the floats 2 will be caused to impinge against the water with their faces 3 parallel, or nearly so, with the surface of the water, and the reaction thus produced, together with the immersion of the floats, will

cause the vessel to be raised bodily until but little, if any, of the hull will remain submerged. When the vessel is thus elevated, its weight is of course supported partly by the hollow 5 wheels and floats and partly by the reactionary effects of the paddles striking or pressing against the water, so that the portion of the vessel—*i. e.*, the wheels—remaining in contact with the water will always be moving in a 10 direction to assist the forward movement of the vessel.

When it becomes necessary or desirable to increase the lifting-power of the mechanism over and above that furnished by the wheels 15 and their hollow floats, I employ to supplement the action of the wheels a series of reciprocating floats, C, applied either to the wheel or to the hull of the vessel, or both combined, as shown in Fig. 1.

20 When applied to the wheels B, the floats C are arranged immediately beyond the outer faces of the floats 2, as shown, and are connected to suitable operating devices, whereby they are caused to be projected quickly as 25 they pass beneath the shaft. The floats C, being thus propelled or driven vertically against the water beneath them and in line with the shaft, the reactionary effect upon the vessel will operate to assist in raising the latter.

30 As is obvious, any improved form of mechanism may be employed for reciprocating the floats C—such, for example, as illustrated in the drawings, wherein the floats C are shown attached at each end to one member of a pair 35 of toggle-levers, 9, the other member of the toggle being pivoted to the side or upon the shaft of the wheel. The center pins, 10, of the toggle are arranged to make contact with suitable stationary cams, 11, affixed to supports 40 on the hull and the outer rail or frame, 12, whereby as the floats C are brought beneath the axis of the wheel the toggle will be straightened and the float driven down.

The reciprocating or walking floats D applied to the hull consist of a hollow float, 13, 45 preferably of the shape shown, secured to the end of a pitman, 14, connected to a crank, 15, on a rotary shaft, 16. The pitman 14 is provided with a pin or block, 16½, sliding vertically in ways 17 on the hull of the boat, so 50 that as the crank revolves the pitman will be caused to oscillate upon the pin 16, while the latter reciprocates vertically in the way 17, whereby the float D, traveling in a circular or 55 elliptical path, whose lower side extends below the surface of the water, will be caused to impinge against the water.

The floats D, being hollow, are made of such a size and proportion that while their lower 60 or striking face will be projected below the water-line as they are caused to move in their circular or elliptical path they will not be wholly immersed, but their upper surface will remain above the water-line; hence the pressure exerted upon the vessel will be always applied in a direction to lift the latter.

In order that the vessel may be raised and

sustained at the proper point to materially diminish the friction of the hull against the water, according to my improvements, it is necessary that a series of the wheels B should be arranged on each side of the hull, (which latter is constructed so as to be comparatively narrow and shallow,) in order to support the latter equally throughout its length. 75

I claim as my invention—

1. In a paddle-wheel such as described, the combination of a series of hollow floats provided with the tangential striking-faces and curved or inclined rear faces, substantially as 80 and for the purpose set forth.

2. The improved paddle-wheel herein described, consisting, essentially, in the combination, with the hollow drum, of the broad and hollow floats having the tangential striking-faces and curved rear faces, substantially 85 as and for the purpose set forth.

3. In combination with the hull of a vessel, a series of buoyant paddle-wheels, substantially as herein described, supported upon opposite sides of the hull, said wheels consisting, essentially, of the hollow central drums extending to or below the bottom of the vessel, and the series of hollow floats having the curved or inclined rear faces and tangential striking 95 front faces, as and for the purpose set forth.

4. In combination with a vessel such as described, a series of vertically-reciprocating floats, as and for the purpose set forth.

5. In combination with a vessel such as described, a series of vertically-reciprocating buoyant floats, as and for the purpose set forth. 100

6. A vessel such as described, provided with buoyant paddles having tangential floats, and 105 in combination therewith a series of vertically-reciprocating floats to supplement the action of the paddles in raising the hull, as set forth.

7. In combination with the buoyant paddle-wheel having the central drum and hollow tangential faced floats, the reciprocating floats located at the ends of the hollow floats and connected to devices for successively projecting them as they pass beneath the shaft, substantially as described. 110

8. In a paddle-wheel for propelling and raising the hull of a vessel in the water, the combination, with the hollow central drum and the hollow paddles or floats secured thereto, and provided with the broad outer face, tangential front face, and curved rear face, of the series of reciprocating floats supported upon the wheel and located beyond the outer face of the hollow floats, and devices, substantially as described, acting upon the reciprocating floats to project them downward as they pass beneath the shaft, as and for the purpose set forth. 120
